UNITED STATES PATENT OFFICE.

ISAAC COOK, OF ST. LOUIS, MISSOURI.

IMPROVEMENT IN FLOUR-PACKERS.

Specification forming part of Letters Patent No. 42,463, dated April 26, 1864.

To all whom it may concern:

Be it known that I, ISAAC COOK, of St. Louis, in the county of St. Louis and State of Missouri, have invented a new and Improved Flour-Packer; and I do hereby declare that the following is a full, clear, and exact description of the same, reference being had to the accompanying drawings, forming a part of this specification, in which—

Figure 1 represents a sectional front elevation of my invention. Fig. 2 is a side elevation of the same.

Similar letters of reference in both views indicate corresponding parts.

This invention consists in a flour-packer the spout of which is made of wood and provided at its bottom end with an auger-chamber and auger rotating on a vertical shaft, in combination with a rising and-falling barrel-platform which is forced up by a weight, and the strain exerted by this weight on the platform is regulated according to the increasing quantity of flour in the barrel by means of a sliding weight and friction-brake in such a manner that the flour throughout the whole barrel is compressed with uniform density by the automatic action of the packer.

The invention consists also in a tappet attached to one of the upright guide-bars of the barrel-platform in combination with a hooked rod connecting with a weighted lever, which is pivoted to the sliding journal-box of the main driving-shaft in such a manner that as soon as the platform has descended to its lowest point the tappet strikes the end of the rod and throws the driving-shaft out of gear with the auger-shaft.

To enable others skilled in the art to make and use my invention, I will proceed to describe it.

A represents a frame, made of wood or any other suitable material, and provided with two grooved uprights, *a*, which form the guides for the rising-and-falling platform *B*. This platform is suspended from two ropes or chains, *b*, which are secured to the standard *c*, rising from its middle, one on each side, and said standards are steadied by braces *d*, so that the platform is evenly supported in the middle and at its four corners.

The ropes *b*, from which the platform *B* is suspended, are connected to the peripheries of rollers *e*, which are firmly keyed to a hori-

zontal shaft, *C*. This shaft has its bearings in the uprights *a* of the frame *A*, and it extends through said uprights on both ends. One end bears the drum *D*, and a rope, *f*, which is fastened at one end to the periphery of this drum and wound round it several times, extends from the same over a pulley, *g*, and supports the weight *F*. This weight moves up and down in a box, *E*, extending throughout the full height of the frame *A*, or nearly so, and it must be sufficiently heavy to counteract the weight of the platform *B* with the barrel, and to exert beside an upward strain on said platform of such a power as may be required to raise the platform and barrel up to the auger ready for packing.

In order to compensate for the increasing weight of the barrel as the same fills with flour, and to produce the desired pressure for packing, a pulley, *G*, is secured to that end of the shaft *C* opposite the drum *D*, and to the center of this drum a pinion, *h*, is firmly fastened. This pinion gears into a toothed segment, *i*, which oscillates on a pivot, *j*, inserted in the outside of one of the uprights *a*, and it connects by a rod, *k*, with a carriage, *l*, from which a weight, *m*, is suspended, as clearly shown in Fig. 2 of the drawings.

The carriage *l*, which supports the weight *m*, slides in and out on a lever, *H*, which is pivoted to the outside of one of the uprights *a*, under the pulley *G*, and which is connected to the end of a strap, *n*, that extends round an arc of one hundred and eighty degrees (more or less) of the pulley *G* in such a manner that by depressing the front end of the lever said strap is drawn up tight against the periphery of the pulley and acts as a brake. The force with which this brake is applied naturally depends upon the power with which the front end of the lever *H* is depressed, and said force increases if the carriage and the weight *m* are moved toward the outer end of said lever, and by moving them in the opposite direction the force with which the brake is applied decreases.

At the beginning of the operation the platform, with the barrel, is raised to its highest point, and the segment *i* and carriage *l* are in the position shown in red outlines in Fig. 2. As the barrel fills the platform descends and the pulley *G* turns in the direction of the arrow marked on it in the same figure, and the seg-

ment moves in the direction of the arrow marked thereon. By these means the carriage *l* is gradually moved toward the outer end of the lever *H* and the force with which the brake is applied increases until the platform has reached its lowest point. The motion of the carriage *l* is regulated by moving the pin which connects the rod *k* with the toothed segment *i* nearer to or farther from the pivot *j*, on which said segment oscillates, and it will be readily understood that by increasing the distance between said pin and pivot the motion of the carriage *l* is increased, and vice versa.

The flour is introduced in the barrel through a spout, *I*, which is secured in the middle of the frame *A* over the platform *B*. This spout is made of wood, and connected to its lower end is the auger-chamber *J*, which is made of sheet metal. *K* is the auger, which is provided with two or more blades, and connected to the lower end of a vertical arbor, *L*, extending down through the spout. Said shaft has its bearings above in a cross-bar, *o*, secured between the uprights *a* of the frame *A*, and below at a short distance from the auger in a cross-bar, *p*, that is fastened to the lower edge of the wooden part of the spout.

A bevel-wheel, *g*, is mounted on the upper end of the arbor *L*, and said arbor receives a rotary motion by another bevel-wheel, *r*, which is secured to the driving-shaft *M*. That end of this shaft next to the bevel-wheel *r* has its bearing in a box, *s*, to which a vertically-sliding motion can be imparted, and by moving said box up the bevel wheel *r* is thrown out of gear with the wheel *g*, and the motion of the arbor *L* stops, and by moving the box down the wheel *r* is thrown in gear with the wheel *g* and the arbor *L* rotates. This sliding motion of the box *s* is effected automatically by a lever *N*, which is pivoted to its

outside, and which has its fulcrum on a projection, *t*, bearing on the cross-bar *o*. A weight, *O*, suspended from its rear end, forces the box *s* up, and a rod, *P*, which is connected to its front end, serves to pull said front end together with the box down and to throw the bevel-wheels *g* *r* in gear with each other. This rod extends down to the lower part of the frame *A*, and its lower end is bent so that it can be made to catch over a stop, *u*, secured to one of the uprights *a*. If the rod is pulled down so that it hooks over the stop *u*, its lower end is in such a position that a tappet, *v*, secured to the front side of one of the standards on the platform *B*, will strike the same whenever said platform descends low enough, and by the action of said tappet the rod is caused to release the stop *u*, and the weight *O* causes the rear end of the lever *N* to descend, and the box *s* is raised. By this arrangement the motion of the auger is stopped automatically as soon as the barrel has been filled up, and a waste of flour is avoided. The tappet *v* is adjustable up and down, so that it can be set to correspond to the height of different barrels.

A flour-packer can thus be constructed which is very compact, cheap, and reliable in its operation.

What I claim as new, and desire to secure by Letters Patent, is—

The weighted lever *N*, hooked rod *P*, and stop *u*, in combination with the tappet *v* on the platform *B*, and with the sliding box *s* of the driving-shaft, constructed and operating in the manner and for the purpose substantially as set forth.

ISAAC COOK.
